UNITED STATES PATENT OFFICE.

HENRY R. GOGAY, OF COLUMBUS, OHIO, ASSIGNOR TO SOLAR METAL PRODUCTS COMPANY, INC.

HOLLOW METAL DOOR.

1,323,753.

Specification of Letters Patent.

Patented Dec. 2, 1919.

Application filed October 24, 1917. Serial No. 198,264.

To all whom it may concern:

Be it known that I, HENRY R. GOGAY, a subject of the Crown of Great Britain, and resident of Columbus, in the county of Franklin and State of Ohio, have invented a new and useful Improvement in Hollow Metal Doors, of which the following is a specification.

In the manufacture of hollow metal doors it has heretofore been necessary to wait until the lock to be used in connection therewith was known before completing the door, thus preventing the stocking up of a large supply of doors and also requiring a special set of dies and tools to be used for each particular size and style of lock.

The object of my invention is to produce a type of hollow metal door which may be completed in large quantities, blanked out to receive any size or style of lock, thus materially reducing the cost of manufacture and also permitting the rapid filling of orders from stock.

A further object is to provide a hollow metal door of the above character in which the lock is very firmly held in position and in which the door is reinforced around the lock.

My invention includes a hollow metal door having the edge of its front stile blanked out to fit a sub-holder for the lock, which sub-holder is itself blanked out to fit the face plate of the particular lock to be applied to the door, reinforcing means being employed for the lock and simple means being employed for securing the lock face plate to the sub-holder and the sub-holder to the door.

A practical embodiment of my invention is represented in the accompanying drawings in which,

Figure 1 is a detail face view of a hollow metal door with my invention applied thereto.

Fig. 2 is an edge view of the same,

Fig. 3 is a section taken in the plane of the line III—III of Fig. 1,

Fig. 4 is a section taken in the plane of the line IV—IV of Fig. 2,

Fig. 5 is an enlarged section taken in the plane of the line V—V of Fig. 1, and Fig. 6 is an enlarged detail section taken in the plane of the line IV—IV of Fig. 2.

The edge of the front stile 1 of the door is blanked out to fit a sub-holder 2, prefer-

ably of channel form, which sub-holder is sufficiently long to permit it to be blanked out to fit the face plate 3 of any size or style of lock. An open front channel reinforcement has its back 4 bridging the space between the sides of the front stile and has its sides 5 extended forwardly along the inside of the front stile to points along the front edge of the stile. This reinforcement is preferably welded at suitable points indicated by the dotted circles 5* to the front stile to reinforce the same around the lock.

The sub-holder may be attached to the door by means of upper and lower sub-holder clips 6, having portions overlapping the top and bottom of the sub-holder. These clips are preferably provided with wings 7 welded at suitable points indicated by the dotted circles 7* to the sides 5 of the channel reinforcement. Screws 8 may be employed for securing the top and bottom of the sub-holder to the overlapping portions of the said clips 6. The face plate 3 of the lock may be secured to the sub-holder 2 by providing the sub-holder with clips 9, which may be welded at suitable points indicated by the dotted circles 9* to the sub-holder and provided with portions overlapping the top and bottom of the face plate. Screws 10 may be provided for securing the top and bottom of the face plate to the said clips.

To keep the lock in position and to prevent undue strain thereon, I preferably provide a clip, the back 11 of which is secured to the back 4 of the reinforcement and the branches 12 of which engage the sides of the lock at its back.

The sides of the front stile and the reinforcement are blanked out as shown at 13 and 14, opposite the sides of the lock, for the bolt and latch operating devices of the lock.

The method of applying the lock to any particular size or style of door is as follows: The sub-holder intended for use with such particular lock is blanked out to fit the face plate of the lock. The face plate clips 9 may then be welded to the sub-holder and drilled and tapped to receive the screws 10. The lock and sub-holder may then be assembled by the screws 10. The lock and sub-holder may then be inserted into the front stile which has already been blanked 110

out to receive the standardized sub-holder. The sub-holder and the lock carried thereby may then be secured to the clips 6, 7, by the screws 8.

- 5 While I have described this invention in connection with the attachment of a lock to the front stile of a door, it is obvious that the invention may be employed for attaching a lock of any size and style to 10 any hollow metal structure lending itself to such application; therefore, I do not wish to limit myself to this particular application but intend to cover all equivalents.

What I claim is:

- 15 1. In a hollow metal door arranged to receive locks of various sizes and styles, a sub-holder blanked out to fit a particular lock face plate, a front stile having its edge blanked out to fit the sub-holder, and means 20 for securing the lock face plate to the sub-holder.
2. In a hollow metal door arranged to receive locks of various sizes and styles, a sub-holder blanked out to fit a particular lock 25 face plate, a front stile having its edge blanked out to fit the sub-holder, and means for securing the sub-holder to the stile.
3. In a hollow metal door arranged to receive locks of various sizes and styles, a 30 sub-holder blanked out to fit a particular lock face plate, a front stile having its edge blanked out to fit the sub-holder, and means for securing the lock face plate to the sub-holder and the sub-holder to the stile.
- 35 4. In a hollow metal door arranged to receive locks of various sizes and styles, a sub-holder blanked out to fit a particular lock face plate, a front stile having its edge blanked out to fit the sub-holder, and means 40 for securing the lock face plate to the sub-holder comprising clips overlapping the face plate and screws engaging the face plate and clips.
5. In a hollow metal door arranged to 45 receive locks of various sizes and styles, a sub-holder blanked out to fit a particular lock face plate, a front stile having its edge blanked out to fit the sub-holder, and means for securing the sub-holder to the stile, comprising clips overlapping the sub-holder and 50 screws engaging the sub-holder and clips.

6. In a hollow metal door arranged to receive locks of various sizes and styles, a sub-holder blanked out to fit a particular lock face plate, a front stile having its edge blanked out to fit the sub-holder, and means for securing the lock face plate to the sub-holder and the sub-holder to the stile comprising clips overlapping the face plate and sub-holder and screws engaging the face 60 plate, the sub-holder and their respective clips.

7. In a hollow metal door arranged to receive locks of various sizes and styles, an open front channel lock reinforcement located within the front stile, a sub-holder blanked out to fit a particular lock face plate, a front stile having its edge blanked out to fit the sub-holder, and means for securing the lock face plate to the sub-holder. 65

8. In a hollow metal door arranged to receive locks of various sizes and styles, an open front channel lock reinforcement located within the front stile, a sub-holder blanked out to fit a particular lock face plate, a front stile having its edge blanked out to fit the sub-holder and means for securing the sub-holder to the front stile. 70

9. In a hollow metal door arranged to receive locks of various sizes and styles, an open front channel lock reinforcement located within the front stile, a sub-holder blanked out to fit a particular lock face plate, a front stile having its edge blanked out to fit the sub-holder, and means for securing the lock face plate to the sub-holder and the sub-holder to the stile. 80

10. In a hollow metal door arranged to receive locks of various sizes and styles, an open front channel lock reinforcement located within the front stile, a sub-holder blanked out to fit a particular lock face plate, a front stile having its edge blanked out to fit the sub-holder, means for securing the lock face plate to the sub-holder and the sub-holder to the stile, and holding means interposed between the lock case and reinforcement. 90

In testimony, that I claim the foregoing as my invention, I have signed my name this 100 10th day of August 1917.

HENRY R. GOGAY.
